UNITED STATES PATENT OFFICE.

JOHN MAGEE, OF MALDEN, MASSACHUSETTS, ASSIGNOR TO MAGEE FURNACE COMPANY, OF BOSTON, MASSACHUSETTS, A CORPORATION OF MASSACHUSETTS.

DESIGN FOR A STOVE OR RANGE.

SPECIFICATION forming part of Design No. 37,229, dated November 15, 1904.

Application filed October 19, 1904. Serial No. 229,183. Term of patent 14 years.

To all whom it may concern:

Be it known that I, JOHN MAGEE, a citizen of the United States, residing at Malden, in the county of Middlesex and State of Massachusetts, have invented a new, original, and ornamental Design for a Stove or Range, reference being had to the drawing, showing the same in perspective.

Having shown my invention, what I claim

as new, and desire to secure by Letters Patent to of the United States, is—

The ornamental design for a stove or range as shown.

JOHN MAGEE.

In presence of—

F. R. PERRY,
LOUISE C. MAGEE.
